UNITED STATES PATENT OFFICE.

GEORGE D. DUDLEY, OF LOWELL, MASS., ASSIGNOR TO EDWD. P. WOODS,
DANL. SHERWOOD, AND CYRUS H. LATHAM, OF SAME PLACE.

IMPROVEMENT IN WIRES.

Specification forming part of Letters Patent No. 145,285, dated December 9, 1873; application filed
January 6, 1873.

To all whom it may concern:

Be it known that I, GEORGE D. DUDLEY, of Lowell, in the county of Middlesex and State of Massachusetts, have made certain Improvements in Wire from which wire goods are manufactured, of which the following is a specification:

The wire from which certain kinds of wire goods are manufactured should be of a certain configuration in cross-section, in order that when such wire is finished and twisted the face of the wire that reflects the light will cause it to present a pleasing and tasteful appearance, which is due to the angle at which the light shall strike it.

The object of this invention is to produce a wire that will have the form adapted to such purpose; and it consists in the form of the wire, as will be more fully described hereinafter.

In the drawings, Figure 1 is a longitudinal view of the wire; Fig. 2, an enlarged transverse section of same; Fig. 3, a view of the wire partially twisted; Fig. 4, a view of two wires twisted together, and Fig. 5 a view of the rollers that form the grooves in the wire.

A represents a wire that is grooved at or nearly at right angles to its face, longitudinally, by being drawn through between rollers to make the grooves into each side, of however many sides the wire may be formed, as it may

be of rectangular, triangular, or have any number of sides desired. The grooves may be formed when the wire is first drawn, or they may be made by a subsequent or secondary operation by passing the wire, already in rectangular or round shape, between rollers adapted to form the grooves in the face of the wire. The forming the grooves in the wire tends to strengthen the wire by making it more fibrous and compacting the fiber, while it also tends to greatly stiffen it. After the wire is thus formed it can be finished by plating or galvanizing, in order to prevent oxidation, or to beautify the surface of the wire, and when so finished it is twisted, as seen in Figs. 3 and 4, when it forms a surface having an improved and beautiful appearance.

The wire having the grooves thereon, as above described, and when finished, is used for making what is known in the market as "twisted-wire goods."

Having thus described my invention, what I claim, and desire to secure by Letters Patent, is—

The wire A, having the longitudinal grooves in its faces, as herein described, as a new article of manufacture.

GEORGE D. DUDLEY.
